UNITED STATES PATENT OFFICE.

JOHN T. SKINNER, OF LAWRENCE, KANSAS.

RHEOSTAT-RESISTANCE CAR-HEATER.

1,121,674.

Specification of Letters Patent. Patented Dec. 22, 1914.

Application filed February 7, 1914. Serial No. 817,252.

To all whom it may concern:

Be it known that I, JOHN T. SKINNER, a citizen of the United States, residing at Lawrence, in the county of Douglas and State of Kansas, have invented a new and useful Rheostat-Resistance Car-Heater, of which the following is a specification.

The present invention relates to the heating and ventilating equipment of electrically propelled cars and is designed to provide a practical and convenient means whereby the resistance elements ordinarily employed in connection with the electrical equipment of such cars may be utilized as the means for supplying heat for maintaining the proper temperature of the passenger compartments, as well as for creating, where desired, currents of air for the purpose of ventilation.

20 The apparatus of the present invention is designed primarily for the purpose of utilizing the energy heretofore wasted in the form of heat which is ordinarily dissipated and lost and which energy is necessarily consumed in effecting the proper control and regulation of the motors, lights, etc., of the car equipment.

Referring to the accompanying drawings,—Figure 1 is a front view of a rheostat equipment with the front sliding metal door removed; together with a part of the resistance grids, to show the path of the air circulating through the compartment. Fig. 2 is an edge view of the arrangement shown in Fig. 1, as it appears with the edge panel, heat resisting panel and grids removed, this view also showing the path of the air circulating in the compartment, and also a portion of the headlight resistance heater where 35 it joins the main heater for the circulation of air through both of the heaters. Fig. 3 is a sectional elevation of a car platform or vestibule showing the heater in position therein. Fig. 4 is a diagrammatic end view; 40 Fig. 5 and Fig. 6 a diagrammatic top plan view of the arrangement shown in Fig. 3. Fig. 45 6 is an elevation of a motor rheostat resistance grid bank, showing the form of the end supports for facilitating the mounting 50 of the rheostat in the heater shown in the preceding figures. Figs. 7 and 8 are a cross section and an inside elevation respectively of the end frame or support of the rheostat. Fig. 9 is a section (on the line 9—9 Fig. 55 10) longitudinally through the top compartment of the main heater, illustrating

the arrangement of the drain table. Fig. 10 is a section (on the line 10—10 Fig. 9) in a plane at right angles to the plane of the section of Fig. 9. Fig. 11 is an elevation of the front sliding metal door having a small door therein through which air from the headlight rheostat heater passes into the main heater. Figs. 12 and 13 are vertical and horizontal cross sections respectively of the door shown in Fig. 11. Fig. 14 is a perspective view of the headlight rheostat resistance heater.

Like letters of reference in the several figures indicate the same parts.

In carrying the invention into practice, the rheostat or resistance elements for the motor equipment, as well as the lights, such, for example, as the headlight of the car, are grouped together in suitable compartments 75 through which a current or currents of air are caused to travel into the passenger compartments or space of the car structure. Suitable provision is made whereby the air traveling through the rheostat compartments 80 may be regulated or, where weather conditions do not make it desirable to heat the cars, the air may be discharged freely so as to maintain a proper cooling and ventilating condition around the rheostats for 85 dissipating the heat generated in their normal operation. The arrangement is such that the ventilation and cooling of the rheostat elements is taken care of, regardless 90 of the use to which the heat generated thereby is put, and this condition makes it desirable that the said rheostat elements should be located outside of the passenger space of the car, so that the heat may be 95 dissipated when it is not desired to utilize the same for heating purposes.

While the rheostat elements may be located in any suitable position on the car, the arrangement preferred is one which lends itself favorably to installation on cars at 100 present in use, without requiring a rebuilding or re-designing of the car structure in any particular.

Referring particularly to Figs. 1 and 2, which represent a rheostat compartment 105 designed for the motor equipment rheostats, the reference letters A and B indicate a metal framework preferably of substantially rectangular form and adapted to be inclosed by insulating panels D having a metal covering E, the front of said compartment being formed by a sliding door J shown in

detail in Figs. 11, 12 and 13. Above the compartment formed by the frames A and B, there is located an entrance compartment T having one end open for the free flow of air into the main compartment, and in order to prevent the entry of water it is preferably provided with an inclined water table *t* and a deflector *t'*, thus permitting the free entry of air downwardly into the main 5 rheostat compartment, which air may be caused or allowed to escape through an opening *g* which is conveniently in communication with the passenger space of the car body. The preferred and, it is believed, 10 the most practical arrangement is that shown in Figs. 3, 4 and 5, where the rheostat compartment or heater is located on the platform or in the vestibule of the car, in such position that the air passing out 15 through the opening G will be discharged into the body of the car.

The frames A at the edges of the rheostat or heater compartment are provided with angle iron brackets C extending from front 20 to rear of the heater and spaced apart vertically a proper distance to receive the rheostat grids or elements and form rigid supports therefor. By reference to Figs. 1, 6, 25 7, and 8, it will be seen that each of the rheostat elements or grids is provided with an end frame I preferably in the form of a cupped metal frame, whereby they may be made relatively thin and yet amply rigid to withstand any bending stress. Said frames 30 are connected together by longitudinal bolts I' and at an intermediate point they are provided with outwardly projecting brackets *i* adapted to seat on the supports C and when the grids are properly positioned to 35 be rigidly connected with said supports C by suitable bolts *c* whereby the whole framework, including the frames of the resistance elements, will be united into a rigid structure. With this construction any one of 40 the rheostat elements or grids may be independently removed from the heater for repair or replacement, and access to them is gained by removing the sliding front J which extends throughout the full width of 45 50 the heater compartment, and when removed leaves the whole front of the compartment open so as to avoid any possible interference with the free removal or free access to the resistance elements.

55 As before stated, the main heater which is inclosed by the edge panels E, top T and front J is adapted to contain the rheostats for the main motor equipment of the car, and in order to augment their heating effect, 60 without exposing the resistance elements of the headlight or other lighting equipment of the car to the possibility of injury, should a blow-out occur in the main resistance elements, said rheostats for the lighting equipment are preferably located in a separate 65

compartment H. For convenience, the said compartment or heater H is located on the car in proximity to the main heater, as shown in Figs. 3 to 5, and air is circulated through it, as shown by the arrows in Fig. 73 2 into the lower portion of the main heater, where it commingles with the air heated by the main resistance elements and flows into the body of the car. For regulating the flow of air from heater H into the main 75 heater, the door J is conveniently provided with an opening controlled by a slide *j*, and the slide *j* is adapted to be adjusted by a set screw handle *j'*.

Obviously, air forcing means may be employed in connection with the heater, either to force the air through the same into the car body for heating the latter, or for keeping the resistance elements cool when the heating of the car body is not an object, but in either event the rheostats are so located 80 that they are susceptible of use as heating elements, and the arrangement is such that the heat ordinarily wasted may be utilized 85 economically. This dispenses with the necessity of providing separate heaters directly in the passenger space of the cars, thus not only saving the cost of installing such heaters, but conserving the energy which is ordinarily wasted as dissipated heat in the normal running of the electrical equipment. 90 95

Having thus described my invention, what I claim as new and desire to secure by Letters Patent of the United States, is:

1. The combination with an electrically driven car and rheostats forming a part of the power equipment, of a heater compartment, exterior to the body of the car, in which said rheostats are mounted, an air duct leading from said heater compartment 100 105 into the body of the car, an air intake duct leading into said heater compartment, and means for excluding moisture from the intake duct, substantially as described.

2. In an electric car, a combined rheostat and heater forming a unit adapted to be secured on the car body and embodying a metal framework, insulating panels inclosing said framework to form a heater compartment, inwardly projecting brackets on 110 115 said framework, rheostat elements rigidly mounted on said brackets one above the other and air intake and exit ducts through which air is supplied to the car, substantially as described.

3. A rheostat resistance heater for electric cars forming a unit adapted to be secured on the car body and embodying a heater compartment having heat insulating inclosing walls and intake and exit openings for air supplied to the car, in combination with rheostat resistance heating elements embodying end frames having outwardly projecting brackets, and brackets rigid with the compartment frame for co- 120 125 130

operation with said first mentioned brackets for supporting the rheostats rigidly in position within the heater.

4. In a rheostat resistance heater for electric cars, the combination with the frame having inwardly projecting angle iron brackets and an inclosing casing to form a heater compartment, of rheostat resistance heater elements embodying cupped end frames having outwardly projecting brackets for coöperation with the angle iron brackets on the first mentioned frame, and fastening means for connecting said brackets.

5. In a rheostat resistance heater for electric cars, the combination with the framework having inwardly projecting rheostat supporting brackets, a heat insulating inclosing casing provided with an air entrance opening at the top, and an air exit opening at the bottom, of a series of rheostat resistance heating elements mounted on said brackets, one above and out of contact with the other, and means for securing the rheostat resistance elements in place.

6. The combination with an electric car 25 having a platform vestibule, of a rheostat resistance heater compartment mounted in said vestibule and having an air intake opening, and an air exit opening leading into the body of the car, and rheostat resistance heater elements mounted in said heater compartment.

7. In a rheostat resistance heater for electric cars the combination with the framework having inwardly projecting rheostat 35 support brackets and a heater insulated inclosing casing provided with an air entrance opening at one end and an air opening exit at the opposite end, of a series of rheostat resistance heating element mounted on said brackets one out of contact with the other and means for securing rheostat resistance elements in place.
